UNITED STATES PATENT OFFICE

RICHARD F. MACK, OF ASTORIA, NEW YORK

INTERRUPTER FOR WARNING SIGNALS

Application filed March 12, 1930. Serial No. 435,285.

This invention relates to signaling devices, and broadly comprehends an attachment for the same which interrupts the sound or light emitted from the device in order to change 5 the character of the sound or light and produce a more distinctive and attractive signal.

The invention more particularly refers to an attachment for automobile horns or warning signals, by virtue of which interruptions 10 in the sound emitted produces a warning signal which more effectually attracts the attention of pedestrians or drivers of other vehicles.

The invention further aims to provide an 15 interrupter for sound propagating or light propagating devices which is in the nature of an accessory or attachment and which may be readily associated with or removed from these devices without necessitating alteration 20 of the same or the employment of special tools or the services of a mechanic.

The invention further aims to provide a 25 signal interrupter, the speed of which may be regulated to vary the character of the signal produced.

Other objects reside in the comparative 30 simplicity of construction and mode of operation of the device and the economy with which it may be produced and installed.

With the above recited and other objects 35 in view, reference is had to the following description and accompanying drawings, in which there is exhibited one example or embodiment of the invention, while the claims define the actual scope of the same.

In the drawings:

Figure 1 is a perspective view of the interrupter in applied operating position on an automobile horn.

Figure 2 is a sectional view through the 40 interrupter applied to a horn.

Figure 3 is a rear view thereof.

Referring to the drawings by characters of 45 reference, A designates a sound propagating device herein illustrated as a horn defining a vibratory air column and formed with an outlet end B. The interrupter constituting the subject matter of the present invention consists of a frame 5 which conforms generally to the configuration of the outlet end

B of the sound propagating instrument A, the frame being provided with an inwardly projecting inner marginal flange or bead 6 which snugly fits within the outlet end B of the instrument or device and which may be 55 retained in place in any suitable manner, such as by means of spring fingers 7 which snap over the external bead C of the outlet end B. The frame 5 has mounted therein for movement a shutter 8 which is designed to alternately open and close the outlet end B of the device A to interrupt the propagation of the vibrations of the air column whereby to produce distinctive and attractive signals different from the signals which are ordinarily produced by the device A. By way of illustration, the shutter 8 is disclosed as being rotatively mounted within the frame 5 on a shaft 9 which is journaled for rotation in diametrically disposed bearing openings 10 and 11 in the frame 5. Any suitable means for rotating the shaft and the shutter 8 which is keyed thereto as at 12, is employed, but, as illustrated, this means is in the nature of a wind wheel 13 having blades or vanes 14, and which wind wheel is secured to the shaft 9. When mounted on the horn of a vehicle in motion, it is obvious that the forward motion of the vehicle will cause the wind wheel to turn, thereby rotating the shaft 9 and shutter 8. 60

When the horn or device A is sounded, the rotation of the shutter in the outlet end B thereof will interrupt the propagation of the vibrations of the air column and, hence, produce distinctive and attractive signals. In 65 practice, the frame 5 will preferably be of annular formation, and by shifting the frame circumferentially on the outlet end B of the horn A, the speed and rotation of the wind wheel may be controlled in accordance with the desires of the user, so that the interruptions may be retarded or advanced to vary the character of the sounds emitted. It is, of course, to be understood that while the interrupter is disclosed as applied to an exterior horn or signal A, it is equally well adapted for those that are arranged under the hood of the vehicle, as the draft from the fan will operate the wind wheel. It is also 70 to be understood within the scope of the in-

vention that the shutter 8 may be operated by other mechanisms which are equivalent of the wind wheel, and that the shutter may be either rotated, reciprocated or otherwise moved to and from an open and closed relation to the outlet B to accomplish the purpose of the invention. It is to be further understood that within the scope of the invention the interrupter may be applied to a light producing and projecting device to interrupt and change the character of the light rays.

What is claimed is:

1. The combination with an audible signaling device including a horn of the vibratory air column type for producing a signal, of means movably mounted in the horn outlet for interrupting the propagation of the vibrations of the air column to vary the quality and character of the sound emitted.
2. The combination with an audible signaling device including a horn of the vibratory air column type for producing a signal, of means movably mounted in the horn outlet for interrupting the propagation of the vibrations of the air column to vary the quality and character of the sound emitted, said means including a frame member connected with the outlet end of the horn and framing the outlet and a shutter mounted for movement within the frame.
3. The combination with an audible signaling device including a horn of the vibratory air column type for producing a signal, of means movably mounted in the horn outlet for interrupting the propagation of the vibrations of the air column to vary the quality and character of the sound emitted, said means including a frame member connected with the outlet end of the horn and framing the outlet and a shutter rotatably mounted for movement within the frame.
4. The combination with an audible signaling device including a horn of the vibratory air column type for producing a signal, of means movably mounted in the horn outlet for interrupting the propagation of the vibrations of the air column to vary the quality and character of the sound emitted, said means including a frame member connected with the outlet end of the horn and framing the outlet, a shutter rotatably mounted for movement within the frame and a wind wheel connected with the shutter for effecting rotation.

Signed at New York in the county of New York and State of New York this 10th day of March, A. D. 1930.

RICHARD F. MACK.
